LOOM

Georg Wiget, Arbon, Switzerland, assignor to
 Societe Anonyme Adolphe Saurer, Arbon,
 Switzerland, a corporation of Switzerland

Application April 27, 1938, Serial No. 204,651
 In Switzerland July 10, 1935

4 Claims. (Cl. 139—256)

This application is filed as a continuation in part of the application of the same inventor Serial No. 89,037, filed July 6, 1936, and is filed for the purpose of meeting the Examiner's objections 5 to the original application on the ground of inoperativeness of the disclosure.

This invention relates particularly to weft-replenishing looms in which bobbins or other weft-filling carriers are transferred one by one from 10 a multiple feeder to loom shuttles, as the weft-filling is exhausted or is about to become exhausted, and is concerned particularly with the devices for clamping the weft-thread as the bobbin is to be discharged from the shuttle and 15 for cutting the thread. In accordance with the invention the clamping device and the cutter are mounted on a swinging lever or carrier which swings toward and from the shuttle box in a horizontal plane. Thereby the structural design 20 as a whole is simplified as compared with an arrangement in which the cutter swings in a vertical plane, the thread picked up by the clamp in the return swing of the lever being more easily drawn out and at the same time being held securely in the clamp, while the cutting of the 25 thread is effected close to the shuttle in the movement of the cutter. The invention will be more fully explained hereinafter with reference to the accompanying drawings in which a convenient embodiment thereof is illustrated, and in 30 which:

Figure 1 is a view in vertical sectional elevation of a mechanism which embodies the invention, the operating elements of which are represented in the positions which they assume when 35 the thread of a bobbin in the shuttle has been so completely or nearly exhausted that the bobbin must be replaced by a full bobbin, a rotatable bobbin feeder being shown.

Figure 2 is a view of the same in sectional elevation on the plane indicated by the broken line 2—2 of Figure 1, looking to the right, shuttle and shuttle box being also shown.

Figure 3 is a plan view of certain of the parts 45 shown in Figures 1 and 2, partly in horizontal section, the lay, shuttle box and shuttle being also shown.

Figures 4 and 5 are detail views, partly in section, illustrating the thread clamping devices in 50 different positions.

Figure 6 is a detail view in section and on an enlarged scale showing the members of the thread clamp in open position, the thread being in position for clamping.

Figure 7 is a view similar to Figure 5, but show-

ing a slightly modified form of the clamping device.

Figure 8 is a view in section and on an enlarged scale of the clamp shown in Figure 7.

Figure 9 is a view generally similar to Figure 5 2, but showing the operating elements in the positions which they have so long as there remains on the bobbin in the shuttle a sufficient amount of thread to render unnecessary the replacement of the bobbin, the weft-feeler, which 10 may be of usual construction being also shown in order that the functioning of the mechanism may be understood as well when the bobbin does not require replacement as when it does require 15 replacement.

Figure 10 is a plan view of some of the parts shown in Figure 9.

As the source of supply of the bobbins to be placed one by one in the shuttle C, as each bobbin is exhausted or nearly exhausted of its 20 weft-filling thread, there is shown a rotatable feeder which comprises a shaft 1 mounted in fixed bearings 2^a and 2^b and two parallel discs 1^a and 1^b adapted as usual to receive the two ends of a plurality of bobbins and present them one 25 by one, in position to be transferred from the feeder to the exhausted shuttle when it is in position in the shuttle box B² at the corresponding end of the shuttle race or lay. Adjustably secured to one of the bearing members, as by a 30 bolt and slot connection 3', is a bracket 3 which receives a vertical pivot bolt 4 on which is mounted to swing in a horizontal plane, toward and from the shuttle race near the shuttle box, a lever arm or clamp and cutter carrier 5. On 35 the lever arm or carrier 5 is mounted a roller 6 to coact with a control arm 7 which is formed with a cam lift 7' and is mounted with capacity for longitudinal adjustment on a spindle 8 which is carried by a forked arm 9' of the hammer-like transerrer 9, by which each bobbin is transferred from the multiple feeder above described to an exhausted shuttle in position to receive it.

A coiled spring 10 on the spindle 8 tends normally to raise the control arm 7 against the roller 6. Also mounted on the spindle 8 is a pusher 11 which, when a bobbin is to be placed in the shuttle, is maintained by the action of the spring 10 with its end in line with a bunter 12 carried by the lay 13. When the control arm 7 is in the position shown in Figure 2, which it occupies when a bobbin is to be placed in the shuttle, the bunter 12, in the forward movement of the lay, will coact with the end 11 of the pusher and so cause the hammer-like transerrer to be swung 50

55

on its pivot 30 against the tension of the spring 31 and transfer the bobbin, which then rests against the stop 32, from the feeder into the shuttle.

5 Loosely pivoted on the bearing member 2^b of the bracket 3 is a spindle 15 which passes through an aperture formed in the lever arm or carrier 5 and receives, between the carrier 5 and a nut 15^a, a spring 14 which tends to swing the lever 10 arm or carrier toward the shuttle race, as indicated by the arrow 5^a of Figure 3. The lever arm or clamp carrier 5 is provided with a curved finger 5' for coaction with a control lever 16 pivoted at 16^a and having secured to its other end 15 a tension spring 16' which tends to move the control lever 16 from the position shown in full lines in Figure 3 to the position shown in dot and dash lines. Also connected to the same arm of the control lever 16, to which is connected the 20 spring 16', is a rod 17 of a weft-feeler which functions in the usual manner and is shown in some detail in Figure 9. It will be understood that in the forward movement of the pusher 11 by reason of its coaction with the bunter 12 the 25 control arm 7 is also moved forwardly, its end being then in alignment with the bunter 12 and that, in the upward movement of the hammer-like transferrer 9, the control arm 7 will be moved rearward under the roller 6 and by reason 30 of its cam surface 7' will be depressed so that the pusher 11 will also be swung downward and its end moved out of alignment with the bunter 12. Therefore there will be no movement of the transferrer 9 and its associated parts unless 35 through the action of the bobbin-feeler represented by the rod 17 the bobbin previously in the shuttle is exhausted and the shuttle is in readiness to receive another bobbin from the feeder.

40 Near its outer or free end the clamp carrier 5 supports on a fixed arm 18 a cutter blade 19 of usual construction, shown in edge view in Figure 3, adapted at the proper time in the forward swinging movement of the carrier 5 to engage and cut, between the nearly exhausted bobbin 5 and the loom shed, the weft-thread B then in the clamped position represented by the line B¹. It will be understood that the cutter edge of the cutter blade 19 is inclined downwardly below the 45 lower edge of the arm 18, with which it cooperates in the nature of a shear blade, so that in the rearward movement of the carrier 5, the sharp edge of the blade 19 contacts the weft thread B and severs it.

45 Also mounted on the swinging carrier 5 is the clamping device which holds the weft-thread between the loom shed and the cutter. The clamping device, as shown in Figures 4 and 5, comprises a relatively fixed member 20, which is grooved longitudinally at its forward end, as indicated at 50 20'. In the longitudinally slotted rear portion of the member 20 is pivoted, as at 21, a multi-armed lever 22 which has a downwardly and forwardly curved arm 22^a, an upwardly projecting tooth 22' and a rearwardly and upwardly curved arm 22''. It has also a rearwardly extended arm 22^b which has pivoted loosely thereon at its forward end, as at 23, a tubular clamping head 24 which can swing sufficiently on its pivot to conform to the grooved portion 20' of the fixed member 20 when the lever 22 is swung so as to move the head 24 into contact with the grooved member 20' and thereby clamp the weft-thread securely. A spring 27 on a spindle 26 pivoted 55 loosely on the lever 22 reacts between the head 70 and the spindle and an abutment 28^a through which the spindle 26 passes freely and in which it is guided, causes the clamping head 24 to be moved toward the grooved portion 20' when the thread is to be clamped and the parts are in the 5 position shown in Figure 5 and also, in known manner, holds the lever 22 yieldingly in the position shown in Figure 4 when the lever has been moved into that position.

55

60 Pivotedly mounted on a fixed portion of the loom frame is a toothed latch 28 which in the rearward movement of the member 20 with the swinging carrier 5 is engaged by the tooth 22' of the lever 22, whereby in the continued relative movement of the member 20 the lever 22 is swung from the position shown in Figure 5 to the position shown in Figure 4, the pivot 25 of the spindle 26 thus being caused to pass through the straight line from the pivot 21 of the lever 22 to the aperture in the abutment 28^a through which the spindle 26 moves. This movement of the lever 22, through the coaction of the upwardly and rearwardly curved arm 22'', causes the latch 28 to be raised clear of the tooth 22'. In the operation of the clamp and cutter, after the weft-thread B has come between the clamping jaws 20, 24, an impact arm 29, carried by the lay 13 and therefore having relative movement 30 with respect to the lever 22, coacts with the arm 22^a of the lever 22 and causes the lever to swing from the position shown in Figure 4 to the position shown in Figure 5, in which the thread is securely clamped between the clamping bodies 20, 24.

35 It will be understood that when the weft bobbin is nearly exhausted the weft-feeler causes the rod 17 to be moved to the right in Figure 3 and the control lever 16 to be rocked in a counter-clockwise direction from the position indicated by dot and dash lines and that such movement 40 of the lever 16 permits the swinging carrier 5 to swing from its forward position toward the shuttle race under the influence of the spring 14.

45 It will be understood that when the thread of a bobbin in the shuttle C is completely or so 50 nearly exhausted as to require the replacement of the bobbin by a full bobbin, the operating elements being in the position shown in Figure 2, the bunter 12 carried by the lay 13 in its forward movement contacts the end of the pusher 11 and thereby causes the transferrer 9 to swing on its pivot 30 and so transfers a filled bobbin from the rotatable feeder into the shuttle C, ejecting the exhausted bobbin at the same time. Obviously, until it is necessary to place a filled bobbin in 55 the shuttle the transferrer 9 must be inoperative and to permit this the pusher 11 must be held out of the path of the bunter 12. The initiating of the movement of the operating elements necessary to effect this result is effected by the operation of the usual weft-feeler shown at 41 in Figure 9 having a fork 42 which normally rests lightly on the filled bobbin but permits the feeler 41 to fall when the thread of the bobbin is nearly exhausted. An arm 43 of the feeler overlies the 60 arm 44 of a two-armed lever 44, 45, the arm 45 underlying an arm 46, which is pivotally connected to a lever 47 mounted on shaft 45'. A second lever 47', also mounted on shaft 45', is pivotally connected to the rod 17 previously referred to. When the weft-feeler 41 drops the arm 45 lifts the free end of the arm 46 into engagement with a hooked arm 48 which is pivotally connected with one arm of a two-armed lever 49 which is continuously oscillated by a cam 75

50 on a loom shaft 51. In this manner, as is well understood, the rod 17, being in the position shown in Figures 9 and 10, has imparted to it a longitudinal movement toward the right causing, 5 through the bell crank lever 17' and the connecting rod 17'', the control lever 16, which normally locks the protector lever 5, to be rocked in counterclockwise direction to unlock the protector 5, which permits the protector lever 5, under 10 the influence of its spring 14, to swing toward the slay in the position shown in Figure 3. When the shuttle has not entered the shuttle box completely, as is for instance indicated in Figure 3 by dot-and-dash lines, the shuttle 15 strikes, on the slay swinging forwards, against the arm 18 with the cutter blade 19, which is fixed on the protector lever 5, causing the protector lever 5 to be rocked forwards in opposition to its spring 14 together with the blade 19 20 and the clamping device 20, 24. The forward swing of the protector lever 5 has the result that its roller 6 will run over the cam portion 7' of the control surface of the control arm 7, whereby the pusher 11 is swung downwards, so that the 25 pusher will not coact with the bunter 12 and the change of bobbins will thus be prevented.

When, however, the shuttle is in the correct position in the shuttle box, it does not prevent the swinging of the protector lever. During this 30 swinging motion the lever 22 provided with the clamping head 24 first of all strikes with its projecting tooth 22' against the latch 28 (Figure 5) causing the multi-armed lever 22 to perform a rocking motion in the clockwise direction, where- 35 by the clamping head 24 is lifted out of the grooved surface 20' of the lower part 20 and the clamping device is thereby opened, as shown in Figure 4. During this rocking motion of the lever 22 the pivot pin 25 of the spindle 26 will 40 pass from above to below the plane connecting the pivot pin 21 of the lever 22 with the guiding eye provided for the bar 26 in the flange 20^a of the lower part 20, so that the pivot pin 25 of the spindle 26 will have passed beyond the dead center position and is now secured in the open position 45 through the action of the spring 27 of the lever 22 (Figure 4). After the weft thread B has come between the clamping head 24 and the lower part 20, an impact arm 29 provided on the 50 slay 13 will strike, as shown in Figure 4, against a downwardly directed arm of the lever 22, whereupon the said lever is swung into the closed position (Figure 5). The lever 22 will then remain in the closed position, so that the clamping 55 device 24, 29 will clamp the piece of thread B' projecting from the edge of the woven fabric D (Figure 3), which piece of thread is then cut off in a known manner from the bobbin by the cutter 19 under the influence of a further move- 60 ment of the bunter.

After the weft thread has been cut off from the bobbin, the insertion of a fresh bobbin takes place as follows:

When the protector lever 5 performs the last 65 portion of its rocking motion towards the slay, the roller 6 of the protector lever 5 runs downwards over the cam surface 7' of the control arm 7, whereby the control arm 7 and the pusher 11 are brought under spring action into the position 70 shown in Figure 2. The pusher 11 will then strike against the bunter 12 provided on the slay 13, whereupon the transfferer 9 is rocked about its pivot pin 30 in opposition to the pull of a tension spring 31, so as to insert a fresh bobbin A 75 from the rotatable feeder 1 into the shuttle. The

transfferer 9 is subsequently swung back by the tension spring 31 into its position of rest against the stop 21. The rotatable feeder 1 is ratched in a known manner each time by one step, bringing the next following bobbin A, which is 5 to be inserted, against the stop 32 (Figure 2) and thus fixes the position of the rotatable feeder for the next bobbin.

The return swing of the protector lever is brought about through the control lever 16, 10 which is actuated by the rod 17'', setting itself again into the position shown in Figure 3 in dot-and-dash lines, pressing against the finger 5' and thereby moving the protector lever 5 back against the action of its spring 14. On the 15 protector lever 5 swinging backwards the thread portion B' is loosened.

The piece of thread B' which projects from the edge of the woven fabric is cut off in a known manner by a second pair of shears not necessary 20 to be shown, close to the edge of the woven fabric, either in phase with the motion of the slay or in dependence on the bobbin change.

At the next change of bobbins and the consequent new rocking motion of the protector lever 25 5 towards the slay, the multi-armed lever 22 is again opened through the coaction of its projecting tooth 22' with the shoulder of the latch 28 and the above described procedure is repeated 30 again.

The control arm 7 which coacts with the roller 6 of the protector lever 5 is adjustable in its longitudinal direction on the spindle 8, for the purpose of which the control arm 7 is provided with a longitudinal slot 7'' (Figures 2 and 3). This 35 adjustability of the control arm 7 enables the moment of coaction of the said roller 6 with the cam portion 7' of the control surface of this control arm 7 to be regulated.

The clamping device shown in Figures 7 and 8 40 has on the lever 22 a flat clamping jaw 24^a which is pivoted on the cross pin 23^a and is capable of coacting by means of a groove with the lower part 20^a which has a corresponding convex counter surface 20' (Figure 8). On the multi- 45 armed lever 22 is a pin 33 (Figure 7) which engages in a hole 34, of slightly larger diameter, of the jaw 24^a, whereby the latter is capable of a limited rocking motion on the lever 22, for enabling it firmly to grip the thread which is to be 50 cut off between the parts 24^a and 20^a.

The control arm 7 and the pusher 11 may 55 together form a single member.

It will be understood that various changes in details of construction and arrangement can be 60 made to suit different conditions and that, except as pointed out in the accompanying claims, the invention is not restricted to the particular construction shown and described herein.

I claim as my invention:

1. In a loom, the combination with a lay and shuttle box, of a carrier mounted to swing toward and from the lay in a horizontal plane, a weft-thread clamping device mounted on the carrier and comprising a member stationary with 65 respect to the carrier, a lever pivoted on the stationary member and having an arm with a clamping head to coact with the stationary member, a spring supporting spindle pivoted on the lever, a guide for the free end of the spindle, and 70 a pressure spring interposed between the head of the spindle and the guide, and means coacting with the lever in the swinging movement of the carrier to cause the pivotal connection of the spindle with the lever to move across the 75

straight line from the pivot of the lever to the guide.

2. In a loom, the combination with a lay and shuttle box, of a carrier mounted to swing toward and from the lay in a horizontal plane, a weft-thread clamping device mounted on the carrier and comprising a member stationary with respect to the carrier, and a lever pivoted on the stationary member and having an arm with a clamping head to coact with the relatively stationary member and having also an arm extended therefrom, and a pivoted latch arranged to coact with the lever in the movement of the carrier to cause it to turn on its axis to move the clamping head from the relatively stationary member, the last mentioned arm of the lever coacting in the turning movement of the lever to move the latch out of engagement with the lever.

3. In a loom, the combination with a lay and a shuttle box, of a carrier mounted to swing toward and from the lay in a horizontal plane, a

weft-thread clamping device mounted on the carrier and comprising a support and a thread clamping member stationary with respect to the carrier, a multi-armed lever mounted on the support and having a second thread clamping member, one of said clamping members having a channel portion for the reception of the first mentioned clamping member, whereby the weft-thread will be clamped transversely therebetween, means to rotate the multi-armed lever in the swinging movement of the carrier, and means for locking said multi-armed lever at each end of its rotary movement.

4. A device as set forth in claim 3 having a locking spindle pivotally mounted on the multi-armed lever in off-center relation to the pivot of the multi-armed lever, a flange on the support for confining the free end of the spindle, and a spring mounted on the spindle between its pivotal point and said flange.

GEORG WIGET.
